[57] **CLAIM**

The ornamental design for a paddle latch, as shown and described.

DESCRIPTION

FIG. 1 is a top plan view of a first embodiment of a paddle latch showing my new design;

FIG. 2 is an end elevational view thereof;

FIG. 3 is an opposite end elevational view thereof;

FIG. 4 is a bottom plan view of a second embodiment thereof, the sides and ends being identical in appearance to the first embodiment;

FIG. 5 is a side elevational view thereof;

FIG. 6 is a side elevational view thereof;

FIG. 7 is a top plan view of the second embodiment thereof;

FIG. 8 is a bottom plan view of the first embodiment thereof;

FIG. 9 is a reduced top perspective view of the first embodiment thereof; and,

FIG. 10 is a reduced bottom perspective view of the first embodiment thereof.
